UNITED STATES PATENT OFFICE.

FREDERICK H. HAMMER, OF HIGHLAND PARK, MICHIGAN.

DEVICE FOR PRINTING PHOTOGRAPHS.

1,106,143.

Specification of Letters Patent.

Patented Aug. 4, 1914.

Application filed August 25, 1913. Serial No. 786,355.

To all whom it may concern:

Be it known that I, FREDERICK H. HAMMER, a citizen of the United States, and a resident of Highland Park, in the county of Wayne and State of Michigan, have invented a new and Improved Device for Printing Photographs, of which the following is a specification.

This invention relates to means for printing pictures from negatives by the photographic process, and especially to that type of printing devices whereby the picture may be printed many times larger if desired, than the negative from which it is produced; and its object is to provide a simple and effective printing mechanism of this type which can be quickly and easily adjusted and which can be manufactured at comparatively low cost.

This invention consists in combination with an adjustable support for the printing paper, of a case and collapsible supports therefor, of telescoping connections between the case and paper support, of a pair of glass plates within the case so positioned that the grooves will be at substantially right angles to each other, an electric lamp within the case, and a proper reflector on the opposite side of the lamp from the grooved plates.

It further consists in combination with the construction above set forth, of adjustable jaws for holding cameras of any desired type which may be employed with this projecting device, between the grooved plates and the paper support.

In the accompanying drawings Figure 1 is a detail of the two grooved glass screens which are employed to diffuse the light employed for printing. Fig. 2 is a perspective of my entire construction, including a camera mounted thereon. Fig. 3 is a perspective of the front end of the device showing the jaws for holding the camera in position. Fig. 4 is a central vertical section of this improved projecting mechanism.

Similar reference characters refer to like parts throughout the several views.

The invention embodied in the accompanying drawings consists of a case 1, preferably of sheet metal and rectangular, having a top 2 and a front end 3. This case may be provided with sockets 4 adapted to receive the upper ends of the legs 5, which are pivotally secured to the inner sides of the side-bars 6 of a slidable frame having ends

7 and a cross-bar 8. This frame telescopes in a second frame which may have side-bars 9 and one end bar 10, a brace 11 being preferably secured to the outer ends of the bars 9 and serving to position them with reference to the inner slidable frame. The bars 9 are slidable in the guides 13 secured to the base 14, to which base may be hinged a toe-piece 15 which connects to the board 16. A pivoted link or brace 17 may be employed to hold this board 16 at right angles to the base 14. The printing paper upon which the light is to be thrown may be secured to the board 16 by any desired means, 70 thumb tacks preferred.

The case 1 is provided at its rear end with an opening to receive the fixture 18 of an electric light socket 19 into which an electric lamp 20 may be screwed. Wires 21 and 22 may lead to a current source of any desired character. A concave reflector consisting of any desired number of flat plates 24, secured together by means of a shell 25, preferably of metal, may be mounted on the socket 19, and so constructed, that the rays of light will be thrown forward. The result is that a very much diffused light reaches the grooved glass plates 26 and 27, which are supported within the case by 85 means of the upright guides 28 and 29 secured to the sides of the case. One of these glass screens is grooved horizontally and the other vertically, as shown in Figs. 1 and 4, and the ridges formed by these grooves serve 90 to diffuse the light, so that the rays of light which proceed from the plate 27 are of uniform intensity over the entire plate. In order to further insure uniformity a small bracket or guide 30 may be secured to the front 3 of the case around the opening therein, to support the ground glass plate 32, which covers the opening within the flanges 33, 34, 35 and 36. A slot 37 in the upper flange 35 permits the introduction of 100 the negative from which the enlarged picture is to be printed, which negatives are guided by small angle bars 38 secured against the side flanges 34 and 36.

As shown in Fig. 2, a camera 40, of any 105 desired type having a detachable back, may be mounted on the case in front of the opening in the front plate 3. To hold this camera in position four brackets 41 and 42 may be connected to the side flanges 34 and 36 as shown in Fig. 3, and in these brackets 110 may be mounted the screws 43 and 44. The

clamps 46 and 47 have shoes 48 that are slide-
able on the upper flange 35 and lower flange
33, and are provided with ears 49. The
ears on one of these clamps are preferably
5 formed with right hand threads and those
on the other clamp with left hand threads
to correspond with the right and left hand
threads on the screws 43 and 44. These
screws are provided with knobs or buttons
10 50 so that they can be turned to cause the
clamps to approach each other or separate,
as may be desired, to grip or to release the
camera 40.

It will be apparent that when the lens of
15 the camera is in proper position so as to
approximately focus the negative which has
been introduced through the slot 37, and
which is held in position by the guides 38,
and the current has been turned onto the lamp
20 20, that proper rays of light will pass from
the lens of the camera toward the board 16,
that a picture will be projected onto the
board, the size of which will depend upon
the different proportions and distances of
25 the parts.

When it is desired to store or to ship this
device, the camera is removed from the case
1, the case is lifted from the supports 5
which are then folded down flat between the
30 side pieces 6, the inner frame and outer
frame are telescoped in the guides 13 of the
base 14, and the brace 17 is slipped off from
one of the pins on either the back 16 or the
base 14, permitting this back to fold down
35 onto the slideable portions of the frame.

The sizes and proportions of the different
parts illustrated in these drawings may all
be modified by those skilled in the art with-
out departing from the spirit of my inven-
40 tion as set forth in the claims.

I claim.

1. In a projecting device for printing pic-
tures from negatives, the combination of a
45 case, means to adjustably support the same
with reference to a printing paper support,
a lamp within said case, a reflector mounted
within the case around the lamp, a pair of
grooved plates of glass mounted adjacent
50 the end of the plate which is toward the
paper support, said plates being positioned
so that the grooves of one plate are at an
angle to the grooves of the other plate and
the grooved sides of the two plates are ad-
55 jacent each other, said case having an open-
ing in the end adjacent said plates, a pair
of adjustable clamps mounted adjacent said
openings, and a projecting lens mounted be-
tween said opening and said paper support.

2. In a projecting device for printing pic-
60 tures from negatives, the combination of a
paper-support and a case, means to support
them, said case having an opening in the side

toward the support, an electric lamp within
the case, a concave reflector mounted at the
rear of said lamp, a pair of grooved glass 65
plates mounted between the opening in said
case and said lamp to break up the rays of
light passing from said lamp and reflector
through said opening, a ground glass plate
across said opening, a lens and lens holder 70
mounted between the case and the paper-
support, and means to secure the lens sup-
port to the case.

3. In a projecting device for printing pic-
tures from negatives, the combination of a 75
paper-support and a case, adjustable means
to position the same relative to each other,
a camera mounted on the case and extending
toward the paper-support, said camera and
case communicating, a source of light within 80
the case, and a pair of grooved glass plates
between the source of light and the camera.

4. In a projecting device for printing pic-
tures from negatives, the combination of a 85
lamp, a lens, a support for the lens and the
lamp and for a negative between them, and
a pair of grooved glass plates mounted be-
tween the negative and lamp.

5. In a projecting device for printing pic-
tures from negatives, the combination of a 90
lamp, a lens, a support for the lens and the
lamp and for a negative between them, a
pair of grooved glass plates mounted be-
tween the negative and lamp, and a concave
95 reflector mounted on the opposite side of the
lamp from said plates.

6. In a projecting device for printing pic-
tures from negatives, the combination of a
100 case having an opening at its front end, a
lamp centrally mounted in said case, a re-
flector at the rear of the lamp to reflect the
light through the opening, a pair of grooved
plates mounted in the case between the lamp
105 and the opening, a pair of clamps mounted
adjacent said opening, a pair of screws to
position the clamps, and an open-back
camera secured between said clamps.

7. In a projecting device for printing pic-
tures from negatives, the combination of a
110 base, a paper-support pivoted thereto, guides
mounted on the base, telescoping frames
mounted in said guides, foldable legs
mounted on one of the frames, a case
115 mounted on the legs, a lamp within the case,
a support for negatives within the case, and
a lens mounted on the case between the nega-
tive and the paper-support.

In testimony whereof I have signed this
specification in the presence of two subscrib-
ing witnesses.

FREDERICK H. HAMMER.
